UNITED STATES PATENT OFFICE.

PINKNEY G. LEWIS, OF MILWAUKEE, WISCONSIN, ASSIGNOR TO EMMA A. LEWIS, OF MILWAUKEE, WISCONSIN.

SHEET-MUSIC TURNER.

No 880,546.

Specification of Letters Patent.

Patented March 3, 1908.

Application filed March 25, 1907. Serial No. 364,233.

To all whom it may concern:

Be it known that I, PINKNEY G. LEWIS, a citizen of the United States, residing at Milwaukee, county of Milwaukee, and State 5 of Wisconsin, have invented new and useful Improvements in Sheet-Music Turners, of which the following is a specification.

The object of my invention is to provide a device by which the several sheets of a musical composition may be successively turned by pressure applied to a pedal by the foot of a player while rendering such composition upon a musical instrument, whereby the annoyance heretofore experienced in manu- 10 ally turning the sheets while rendering a piece of music, is avoided. The liability of turning more than one leaf at a time or of the music dropping and becoming disarranged during the performance is entirely overcome.

20 The construction of my invention is explained by reference to the accompanying drawings in which,

Figure 1 is a perspective of my device as it is used in connection with an ordinary up- 25 right piano. Fig. 2 is a front view, part in section. Fig. 3 is a detail in vertical section, showing the mechanism for communicating motion from one of the two pedal actuated shafts to the vertical shaft. Fig. 4 is a bot- 30 tom view of the supporting frame, showing a portion of the interior and exterior pedal actuated shafts and a part of the mechanism for communicating motion from the respective pedal actuated shafts to the vertical shaft. Fig. 5 is a transverse vertical section drawn 35 on line x—x of Fig. 4. Fig. 6 represents one of the pedals removed from the pedal actuated shaft. Fig. 7 is a side view, and Fig. 8 is a top view of the mechanism for holding 40 and turning the several sheets of a musical composition. Fig. 9 is a side view of the seg- 45 mental gear for operating the sheet supporting arms. Fig. 10 is a detail plan view of the mechanism for communicating motion from the horizontal pedal actuated shafts to the vertical shaft in their normal position, when at rest, and the plate 46 and casing 44' being removed with the tubular portion of the rod 13. Fig. 11 is a similar view of the 50 same in their operative relation to each other as they appear when the pedals are being operated.

Like parts are identified by the same reference figures throughout the several views. 55 The supporting base 1 of my device rests upon the floor in close proximity to the in-

strument 2 in front of which a musical composition 3 is centrally suspended by the leaf actuating arms 4 and clamps 5. Pedals 6 and 7 are employed to actuate the arms and 60 turn the sheets.

Assuming that the several arms are connected with the several sheets of a piece of music and that they are all turned toward the right preparatory to rendering the music, 65 motion is communicated from the pedal 7 to the first and successively to each arm 4 of the series, as follows: from the pedal 7 to the exterior pedal actuated shaft 24 through the pedal supporting arm 8 and from thence to 70 the shaft supported radial arm 25, spring actuated pawl 26, star wheel 12, vertical shaft 13, (a top end view of which is shown in Figs. 10 and 11, the cap 46 being removed) miter gear 14, (located at the upper end of 75 said shaft,) miter gear 15 (meshing with said gear 14) gear supporting shaft 16, miter gear 17, miter gear 18, gear supporting shaft 19, segmental gear 20, segmental gear 21 and from thence to one of said arms 4 of the 80 series, the respective arms 4 of the series being each provided with a spring actuated clamping mechanism 5, which are adapted to engage the respective sheets of music which it is desirous to turn.

85 The pawl 26 is provided with an actuating spring 27' by which it is retained in position to contact with the arms 12' and 12'' of said star wheel 12 and said wheel 12 is provided with six radial arms, or at least one for each 90 of the leaf actuating arms 4 and the stroke of the pawl supporting arm 25 is such as to revolve said star wheel one step, or in the construction illustrated, one-sixth of a revolution with each stroke of the pedal and no 95 further. The star wheel and the pawls 26 and 11 constitute a reversible ratchet feed mechanism. Thus it will be understood that with each downward stroke upon the 100 pedal 7, the star wheel 12 will be revolved one-sixth of a revolution, whereby the segmental gear 20 will be caused to revolve one-sixth of a revolution, and whereby the first arm 4 of the series will be caused to turn a half revolution on its supporting shaft 4' 105 from the right to the left, whereby the first leaf of the musical composition will be turned. With the second stroke of the pedal, the pawl 26 will be brought in contact with the next succeeding radial arm 12' of 110 the series, whereby the next leaf actuating arm 4 of the series will be in like manner

turned and thus in like manner each successive arm 4 of the series will be turned with each downward stroke upon the pedal 7. The radial arms 12" is made slightly longer 5 longitudinally of its supporting shaft than the others, whereby, when the star wheel 12 has performed a complete revolution, the upper end of said radial arm 12" will be brought in contact with the stationary stop 10 22, (see Fig. 3) thus preventing the star wheel from being turned further. When the arms have been thus turned from right to left, they are returned to their former position in their reverse order, by successively 15 pressing downwardly upon the pedal 6. Motion is communicated from the pedal 6 to the star wheel 12 through the arm 8, interior shaft 7', pawl supporting arm 10' and pawl 11, which pawl 11 is pivotally connected with 20 the arm 10' by the screw 27 and is yieldingly retained in position to contact with the radial arms 12' of the star wheel by the spring 11'.

The pawl 11 is located upon the opposite side of the star wheel from the pawl 26, and 25 said pawl, as it moves forward, will contact with said wheel upon the opposite side of its supporting shaft, whereby said star wheel will be revolved in the opposite direction from that which is communicated to it when 30 actuated by the pawl 26.

The segmental gear member 20 comprises five circular disks A, B, C, D and E, all of which are rigidly connected together by a plurality of pins 28, whereby they are all 35 adapted to revolve together and each of the disks A to E inclusive are provided with a segmental set of teeth 29 located in successive segments of the member 20, whereby the sets of teeth 29 on the successive disks, 40 are located along a spiral line extending around the member 20 and come into action successively, as the member 20 is rotated.

Each arm of the series is provided with a gear segment 21 adapted to mesh with the 45 teeth 29 of the corresponding disk. When in either extreme position one of the sides 30 or 31 of the segment is brought in contact with the periphery of the corresponding disk, whereby the further movement of the 50 arm 4 is arrested and said arm will remain at rest and the teeth of the disk are free to pass said gear segment, while the gear segment formed in the next member of the series will be brought in position to act upon the gear 55 segment of the next succeeding arm of the series.

While I have shown the segmental gear 20 formed of a plurality of disks connected together by rods 28, it is obvious that if desired such parts A to E inclusive may be formed integrally from a single piece of metal, but for convenience of construction in cutting the gear segments thereon, they are preferably formed separately and thereafter secured together, when the miter gear 18 is

rigidly secured to the upper disk of the series in position to be acted upon by the gear 17.

While the respective shafts 7' and 24 are adapted as stated to be revolved a partial revolution in one direction by the downward pressure upon said pedals they are respectively adapted to be revolved in the opposite direction by the action of the springs 32 and 33. Said springs 32 and 33 are rigidly connected at one end to one of the arms 34 of 75 the supporting base while their opposite ends are adapted to contact with the respective lugs 35 and 36 of the radial arm 10' and 25 upon the opposite sides of said arm supporting shafts, whereby as the respective pedals 80 are depressed the actuating springs are thrown back by contact with said lugs and as soon as said pedals are released, will react and restore said pedals to their normal position. 85

The clamps 5 each comprise a stationary bracket 37 and spring actuated arms 38, 38. The arms 38 are pivotally connected with the bracket 37 by the pin 39 and pin supporting lugs 40. Said arms 38 are yieldingly retained in contact with the bracket 37 by the spring 41, which spring 41 is supported in connection with said parts upon the pin 39. The central portion of said spring 41 has contact bearings with the supporting arm 4, 95 while its respective ends are wound around said supporting pin 39, and yieldingly bears against said arms 38, whereby said arms 38 are retained in contact with the opposing bracket 37. 100

42 is a rectangular bar which is revolvably supported between the bracket 37 and the arms 38. The shape of said bar 42 is such that when the actuating arm 43 is in the vertical position shown, said arms are yieldingly retained in contact with the sheets by the resilient action of said spring 41. When, however, the arm 43 is turned at right angles to the position shown in Fig. 7, said arms 38 are thrown back and the sheets of music 110 released. The specific construction of the clamping mechanism is not material. 110

The horizontal shafts 7' and 24 are revolvably supported beneath the horizontal arm 44 of the supporting base 1, while the revolvable shaft 13 is inclosed and supported by the stationary tubular casing 44'. The casing 44' is connected with the base 1 by the plate 46 and a plurality of screws 47. The revolvable shaft 16 is inclosed and supported by the stationary sleeve 48, which sleeve 48 is rigidly connected with the casing 44' by the angular connection 49. The segmental gear 20 is revolvably supported upon the shaft 19 within the inclosing sleeve 50. The sleeve 50 is rigidly supported from the shaft inclosing sleeve 48 and said supporting base and connecting mechanism are made sufficiently rigid to retain all of the operative parts in their proper relative position. 125 130

Having thus described my invention what I claim as new and desire to secure by Letters Patent is,

1. In a pedal actuated leaf turning device, the combination of a plurality of leaf actuating arms, each provided with a leaf clamping device, a set of foot actuated pedals, an oscillatory laterally extending shaft for each pedal operatively connected therewith, a vertical shaft operatively connected with the leaf turning arms and ratchet feed mechanism arranged to communicate motion from the laterally extending shafts in opposite directions to the vertical shaft. 10
15. 2. In a pedal actuated leaf turning device, the combination of a plurality of leaf actuating arms, leaf clamping mechanism connected with one end of each of said arms, gear segments rigidly connected with the opposite ends of said arms means for supporting said gear segments and arms one above another around a single central shaft, a plurality of annular disks rigidly connected together in a vertical series, the periphery of each disk being provided with a gear segment and an intervening blank space, said gear segments being respectively adapted to mesh with the respective gear segments of said leaf turning arms, the gear segments of the first and each succeeding disk in the series being located slightly in advance of the gear segment of the next succeeding disk, whereby as said disks are revolved together the gear segments on but one of said disks will act at a time upon the gear segments of 70 said arms, two foot-actuated pedals, two pedal actuated shafts one located within the other, means for connecting one of said pedals with the interior shaft, means for connecting the other pedal with the exterior 75 shaft, a vertical shaft located near the ends of said interior and exterior shafts, a star wheel affixed to the lower end of said vertical shaft, said star wheel being provided with a plurality of radial arms, two vibratory arms, one rigidly connected with said interior shaft and one rigidly connected with said exterior shaft, a pawl pivotally connected with each of said vibratory arms, a spring rigidly connected at one end with each of said vibratory 80 arms and adapted to bear at its opposite end against one of said pawls respectively, whereby said pawls are normally retained in position to contact with the radial arms of said star wheel and with each forward movement 85 to revolve said wheel and vertical shaft a partial revolution, means connected with the upper end of said vertical shaft for revolving said series of disks and moving the leaf actuating arms. 90
95. 4. In a pedal actuated leaf turning device, the combination of a plurality of leaf actuating arms, leaf clamping mechanism connected with one end of each of said arms, gear segments rigidly connected with the opposite ends of said arms, means for supporting said gear segments and arms one above another around a central shaft, a plurality of annular disks rigidly connected together 100 in a vertical series, the periphery of each disk being provided with a gear segment and an intervening blank space, said gear segments being respectively adapted to mesh with the respective gear segments of said leaf turning arms, the gear segments of said disks being so located in relation to each other that but one will act at a time upon the gear segments of said arms, the respective sides of said arm supporting segments being adapted when said segments are 105 110
115. 60. 65. 70. 75. 80. 85. 90. 95. 100. 105. 110. 115. 120. 125. 130. 135.
65. 3. In a pedal actuated leaf turning device,

turned to the limit of their movement in either direction to bear against the blank space of said disk, whereby they are locked in place and prevented from turning except 5 when in mesh with the teeth of said disks, two foot-actuated pedals, two horizontal pedal actuated shafts, a vertical shaft located near the ends of said horizontal shafts, means for communicating motion from one 10 of said horizontal shafts to said vertical shaft in one direction and means for communicating motion from the other horizontal shaft to

the vertical shaft in the opposite direction, and means for communicating motion from said vertical shaft to said series of disks and from thence to said leaf actuating arms, all substantially as and for the purpose specified. 15

In testimony whereof I affix my signature in the presence of two witnesses.

PINKNEY G. LEWIS.
